UNITED STATES PATENT OFFICE.

CHARLES E. WILSON, OF WILKINSBURG, PENNSYLVANIA, ASSIGNOR TO WESTINGHOUSE ELECTRIC AND MANUFACTURING COMPANY, A CORPORATION OF PENNSYLVANIA.

CUT-OUT.

1,289,388.

Specification of Letters Patent. Patented Dec. 31, 1918.

Application filed March 3, 1914. Serial No. 322,180.

To all whom it may concern:

Be it known that I, CHARLES E. WILSON, a citizen of the United States, and a resident of Wilkinsburg, in the county of Allegheny and State of Pennsylvania, have invented a new and useful Improvement in Cut-Outs, of which the following is a specification.

My invention relates to cut-outs such as are employed in connection with electrical circuits, and it has particular reference to mechanisms for controlling the electrical connections of dynamo-electric machines.

My invention has for its object to provide a device of the character indicated above, that is simple and economical in construction and effective in operation to control the circuits of an electrical system.

A second object of my invention is to provide a suitable construction whereby the cut-out may be assembled with the parts of a dynamo-electric machine and form a unitary structure therewith.

In the operation of electrical systems, it has been the usual practice, to provide circuit-controlling mechanisms that are separate and apart, both in structure and in location, from the dynamo-electric machines which they control. In some cases, the cut-out has been attached to the frame of a dynamo-electric machine, but the structures of the respective mechanisms have been separate and distinct.

I have provided a mechanism in which a cut-out and a dynamo-electric machine have certain structural parts in common, the resulting mechanism having a neat and compact arrangement that is economical in construction, since the number of parts and the number of manufacturing operations are reduced. The combined device may be assembled, and the electrical connections permanently made, at the place of manufacture. My invention may be employed with particular advantage in connection with the electrical systems of automobiles which embody generators operating at variable speeds to charge storage batteries.

In the accompanying drawings, Figure 1 is a top view, in plan, of a cut-out constructed in accordance with my invention. Fig. 2 is a side view, partially in elevation and partially in section, of the mechanism of Fig. 1. Fig. 3 is a side view, partially in elevation and partially in section, of a portion of a

dynamo-electric machine, with my invention applied thereto. Fig. 4 is a diagrammatic view of circuits and apparatus embodying my invention.

Referring particularly to Figs. 1 and 2, a cut-out 1 is mounted upon the end casing 2 of a dynamo-electric machine, only a portion of the casing being shown. The casing 2 may be of a suitable non-magnetic material, such for example, as insulating material, a metal or an alloy. The cut-out comprises a plate member 3 of magnetic material and core members 4 and 5 that are respectively surrounded by a coil 6 of coarse wire and a coil 7 of fine wire for series and shunt connection, respectively. The plate member 3 and the core members 4 and 5 are attached to the casing 2 by means of suitable screws 8, insulating washers 9 being interposed between the plate member 3 and the casing 2.

A bar 10 of non-magnetic material, is fixed to the core members 4 and 5 by screws 11 which constitute pole pieces for the core members. A leaf spring 12, preferably of phosphor bronze or other suitable material, is attached, at one end, to the folded end portion 13 of the bar 10. The spring 12 is provided, at an intermediate portion, with an armature member 14 of suitable magnetic material. The outward movement of the spring 12 is limited by the opposite end portion of the bar 10 which is bent to form a hook 15. A contact member 16, which is mounted upon, and connected to, the spring 12, coacts with a contact member 17 that is mounted upon, and insulated from, the bar 10. The coils 6 and 7 are connected to the contact member 17.

It may be desirable, in some cases, to construct the end casing 2 of magnetic material. When such material is employed, the core members of the cut-out may be cast integral with the casing.

Referring now to Fig. 3, a dynamo-electric machine 18, only a portion of which is shown, comprises a series field magnet winding 19, a shunt field magnet winding 20 and a frame member 21. An end casing 22 of suitable magnetic material, such, for example, as cast iron, is fixed to the frame member 21 by suitable screws 23, one of which is shown. The casing 22 is provided, at an intermediate point, with a horizontally extending portion 24 upon which are

two vertically extending projections 25 that are integral with the casing. Only one of the projections 25 is shown, but they are substantially similar in form and size to the 5 core members 4 and 5 of Figs. 1 and 2. The projections 25 constitute the core members of a cut-out 26 which differs in no material respect from the cut-out above described in connection with Figs. 1 and 2.

10 In either form of construction, the cut-out is inclosed by a detachable cover 27 which is held in position by screws or bolts 28 thereby forming a closed compartment on the outside of the end wall or plate 22, 15 whereby the cut-out is entirely inclosed and separated from the field magnet and armature compartment of the dynamo-electric machine. This construction provides a simple means for protecting the cut-out or circuit-controlling mechanism and affords convenient access for the purposes of inspection, adjustment and repair.

Referring now to Fig. 4, the coils 6 and 7 are respectively in series and in shunt with 25 the armature 29 of the dynamo-electric machine 18, the coil 7 being in series with the shunt field winding 20. These connections are made, preferably, within the dynamo structure and form a part of the interior 30 circuits of the dynamo. A storage battery 30 is connected directly to one terminal of the dynamo-electric machine, the other terminal of the battery being grounded, as shown. The contact member 16 is grounded 35 through the spring 12, the bar 10, the core members and the dynamo structure.

It may be assumed that the generator 18 is operatively connected to the engine of an automobile (not shown). When the engine starts under its own power, the generator 20 is driven at an increased speed, and current flows from one terminal of the generator through the series field winding 19, series coil 6, shunt coil 7 and shunt field 25 winding 20 to the other terminal of the generator. As the generator speed increases, a predetermined voltage is reached at which the coils 6 and 7 are sufficiently energized to draw the armature member 14 downwardly 30 against the tension of the spring 12 to effect the engagement of the contact members 16 and 17. The battery-charging circuit, which is thereby completed, extends from one terminal of the generator through the series field winding 19, series coil 6, contact members 17 and 16, spring 12 to ground and 35 through the battery 30 to the other terminal of the generator. The battery 30 will be charged as long as the generator voltage exceeds that of the battery.

In case the generator voltage falls below that of the battery, the direction of flow of current in the charging circuit will be reversed. The series coil 6, which normally 40 assists the shunt coil 7, now opposes the

latter and as a result, the spring 12 draws the armature member 14 upwardly. The charging circuit is thus broken by the separation of the contact members 16 and 17 and it cannot be closed again until the generator voltage has reached the predetermined value at which the cut-out is adjusted to close. 70

Various changes in the structure of my invention may be made by those skilled in the art to which my invention appertains. It is understood that such modifications may be made, without departing from the spirit of my invention, as fall within the scope of the appended claims. 80

I claim as my invention:

1. In a dynamo-electric machine, the combination with a field-magnet frame, of a member constituting an end wall of said frame, an integral projection on the outer side of said member, a circuit-controlling device mounted on said projection, and a detachable cover co-operating with the outer side of said member to form a compartment therewith whereby said device is inclosed and separated from the field-magnet and armature compartment of the dynamo-electric machine. 85

2. In a dynamo-electric machine, the combination with a field-magnet frame, of a member constituting an end wall of said frame, a core formed integral with said member on the outer side thereof, a coil surrounding said core, circuit controlling means associated with said core and coil, and a detachable cover co-operating with the outer side of said member to form a compartment therewith to entirely inclose said core, coil and controlling means and separate the same from the field-magnet and armature compartment of the dynamo-electric machine. 95

3. In a dynamo-electric machine, the combination with an end casing having a pair of projecting portions integral therewith, coils on said projections to form an electromagnet, and an armature member controlled by said electromagnet. 105

4. In a dynamo-electric machine, the combination with an armature winding and a field magnet winding, of a casing member having projecting portions integral therewith, a coil upon one of said projections for connection in series with said armature winding, and a coil upon another of said projections for connection in series with said field magnet winding. 115

5. A cut-out comprising an electromagnet having a core, a stationary bar secured to said core, a leaf spring having one end thereof secured to said bar, and coacting contact members and an armature supported by said bar and spring, said armature being subject to attraction by said core and adapted to actuate one of said contact members. 125

6. In a dynamo-electric machine, the com- 130

bination with an end casing having a horizontally extending portion, of a pair of vertically extending core members that are integral with said portion, and coils surrounding said core members.

7. In a dynamo-electric machine, the combination with an end casing having a horizontally extending portion, of a pair of core members that are integral therewith, coils surrounding said core members, co-operating contact members associated with said cores and coils, and a detachable cover for inclosing said coils and contact members.

8. In a cut out, the combination with a casing member having a pair of integral projecting portions, and coils surrounding the projections, of a stationary member secured to said projections, a movable member secured to said stationary member, and

coacting contact members carried by said 20 members.

9. In a cut-out, the combination with a pair of cores, of series and shunt coils surrounding said cores, respectively, a bar secured to said cores, and co-acting contact 25 members and an armature mounted on said bar, said armature being connected to said bar adjacent to shunt coil and subject to the attraction of both of said cores and adapted to operate one of said contact members.

In testimony whereof, I have hereunto subscribed my name this 27th day of Feb. 1914.

CHARLES E. WILSON.
